UNITED STATES PATENT OFFICE

MARION E. HARLAN, OF SAN FRANCISCO, CALIFORNIA, ASSIGNOR TO A. SCHILLING & CO., OF SAN FRANCISCO, CALIFORNIA, A CORPORATION OF CALIFORNIA

DISPLAY RACK

Application filed April 1, 1931. Serial No. 526,924.

This invention relates to a display rack and more particularly to a wire display rack for displaying spices, extracts and similar goods.

5 One of the objects of this invention is to provide a display rack which is constructed with a plurality of supporting shelves arranged in spaced relation so as to enable the housewife or a prospective purchaser to 10 clearly view the packages which are displayed thereon.

It is a matter of common knowledge that there have been comparatively few devices provided whereby the housewife could keep 15 a supply of spices, extracts and like small packaged goods together and at the same time have them readily accessible for use and inspection. The usual happening is that the smaller packages become hidden from 20 view and therefore difficult to locate upon short notice.

With this in mind, the aim of the invention is to provide a rack on which there may be displayed several different kinds of goods in 25 such a manner as they may be readily distinguished from one another and clearly viewed from any position in front of the rack.

The rack forming the subject matter of 30 this invention is also suitable for use in grocery stores to display goods to the prospective purchasers.

A still further object of the invention is to 35 provide a wire display rack in which the main supporting structure is constructed from a single wire.

Other objects including low cost of manufacture, simplicity and durability will 40 become apparent during the course of the following description.

In the accompanying drawings forming a 45 part of this application and in which like numerals are employed to designate like parts throughout the same,

Figure 1 is a perspective view of the display rack, and

Figure 2 is a vertical sectional view of Figure 1.

In the drawings wherein for the purpose 50 of illustration is shown a preferred embodiment of the invention, the main frame of the display rack is constructed from a single wire and is first bent beginning at one end as at 8 to form a substantially triangular standard having a hypotenuse 10, a relatively short side 12, a base 14, and another side 16 of substantially the same length as the base. The wire is then bent at right angles to the side member 16 and extended longitudinally 55 for a length depending upon the size of the rack desired to form the rear portion 18. The wire is again bent at a right angle to the longitudinal portion 18 in the same manner as before to form a second substantially triangular standard of the same size and configuration as the first standard having a hypotenuse 20, a short front side 22, a base 24, and a rear side 26 of substantially the same 60 length as the base 24. The free end of the wire after completing the frame is welded or otherwise secured as at 28.

It is to be noted in this connection that if so desired the substantially triangular standards may be constructed separately and then connected by longitudinally extending members. However, by constructing the entire frame from a single wire as in the manner described, the number of parts are considerably reduced as well as the cost of manufacture.

Wire members 30 and 32 are bent in the form of steps as is clearly indicated in the drawings and have their rearward ends welded or otherwise secured to the sides 16 and 26 of the standards and their forward ends to the bases 14 and 24 thereof at a distance from the ends depending upon the width of the lower shelf desired.

Longitudinally arranged wires 31 are 85

welded to substantially the midpoint of the horizontal portion 33 of the step members 30 and 32 to provide the shelves on the display rack. Directly above the corners of each of the steps of the members 30 and 32 on the hypotenuse 10 and 20, of the vertical standards, there are welded or otherwise securely fixed longitudinally extending wires 34 against which the packages displayed may rest.

10 In order to prevent small packages falling from the shelves and through the rack, and at the same time to provide a brace for the structure, the upper portions of the members 16 and 26 and the midpoint of the rises of each of the step members 30 and 32 are connected by longitudinally extending members 36.

20 In use, the packages which may be of any shape, size or configuration, are disposed upon the longitudinally extending members 32 forming the shelves and by virtue of their relative position with respect to the longitudinally extending members 34 the package assumes a slightly tilted position rearward 25 with respect to the observer thereby increasing the legibility of the printed matter on the packages.

25 The lowermost longitudinally extending rest member 34 as well as the other longitudinally extending members 34 not only perform the function of providing a rest for the upper portion of the packages displayed, but also prevent the packages from falling forwardly from the shelves. It will thus be seen that the rack forming the subject matter of this application not only provides a rack which is cheap to manufacture, but one which is durable and provides an attractive display, affording the housewife or prospective 40 purchaser a clear and legible view of the packages and the printed matter thereon.

While there is shown only one embodiment of the invention in the accompanying drawings, it is capable of various changes and 45 modifications, without departing from the spirit thereof and it is intended, therefore, that only such limitations shall be imposed thereon as are indicated in the prior art or in the appended claims.

50 Having thus described the invention, what is claimed is:

1. A display rack of the class described comprising a single wire bent to form a pair of spaced substantially vertical triangular standards connected by a longitudinally extending portion of the wire, a wire of stepped formation fixed to the side and base of each standard, longitudinally extending members connecting the horizontal portions of each 55 step forming shelves, and spaced longitudinally extending members fixed to the hypotenuse of each triangular standard forming rests for packages disposed on said shelves.

2. A display rack of the class described, 65 comprising a single wire bent to form a pair

of spaced substantially vertical triangular standards connected by a longitudinally extending portion of the wire, a wire of stepped formation fixed to the side and base of each standard, longitudinally extending members connecting the horizontal portions of each step at their midpoint forming shelves, and spaced longitudinally extending members fixed to the hypotenuse of each triangular standard directly above the corners of each step.

M. E. HARLAN.
